US0D1061825S

(12) United States Design Patent (10) Patent No.: US D1,061,825 S
(45) Date of Patent:  Feb. 11, 2025

(54) STRIPED HOSE

(71) Applicant: NORDSON CORPORATION,
Westlake, OH (US)

(72) Inventors: Jim Keough, Cumming, GA (US);
Justin A. Clark, Suwanee, GA (US)

(73) Assignee: Nordson Corporation, Westlake, OH
(US)

() Term: 15 Years

(21) Appl. No.: 29/750,140

(22) Filed: Sep. 11, 2020

Related U.S. Application Data

(63) Continuation of application No. 29/580,454, filed on Oct. 10, 2016, now Pat. No. Des. 905,207.

CLAIM

The ornamental design for a striped hose as shown and described.

DESCRIPTION

FIG. 1 is an isometric view of a striped hose;

FIG. 2 is a right side view of the striped hose;

FIG. 3 is a left side view of the striped hose;

FIG. 4 is a front view of the striped hose;

FIG. 5 is a rear view of the striped hose;

FIG. 6 is a top view of the striped hose; and,

FIG. 7 is a bottom view of the striped hose.

The broken lines are for environmental purposes and form no part of the claimed design.

1 Claim, 4 Drawing Sheets
